UNITED STATES PATENT OFFICE.

DOMENICK RUFF, OF YOUNGSTOWN, OHIO.

SAFE PROTECTOR.

Application filed July 18, 1924. Serial No. 726,848.

To all whom it may concern:

Be it known that DOMENICK RUFF, citizen of the United States, residing at Youngstown, in the county of Mahoning and State of Ohio, has invented certain new and useful Improvements in Safe Protectors, of which the following is a specification.

This invention relates to a device for preventing unauthorized tampering with or 10 opening of safes, locks, doors, etc.

The principal object is to provide an attachment to be put on the safe door or built in as a regular equipment of a safe, comprising a primary and a secondary gas chamber, so arranged that when an unauthorized attempt is made to disturb the locked condition of a safe, this gas will be released.

The gas which may be used will depend upon the judgment of the person using the 20 same or so that a complete compliance with the regulations of law may be complied with. It is suggested that the gas to be used may be of the most deadly nature or gases known as tear gas, sneezing gas, and gases which 25 have a peculiar effect but not resulting in serious physical injury.

The drawing illustrates a preferred embodiment of the invention. However, it is to be understood that in adapting the same to meeting different conditions, various changes in the form, and minor details of construction may be resorted to without departing from the nature of the invention as claimed and set forth in the drawings:—

Figure 1 is a front elevation of a portion of a safe door, with device attached.

Figure 2 is a cross section taken on line 1—1 of Figure 1.

Corresponding and like parts are referred to in the following description and indicated in the several views of the drawings by like reference characters.

By referring to the drawing, it will be seen in the several views of the drawing, I have provided a circular chamber 1 which is delicately secured to an outer portion 2 of a safe door, by means of screws 3. This circular chamber 1, is provided with a flattened base portion 4 fitting against the outer portion 2. 50 By referring to Figure 1, it will be seen that this circular chamber 1 is placed so as to surround a dial 5 having a central knob 6 which is the outer end of lock shaft 7. Attached to this circular chamber 1, is a frail tube 8, 55 communicating with T-connection 9. This T-connection 9 is fitted with an upwardly

extending tube 10 provided with a valve 11 which is connected to an upper gas chamber 12. There is secured to the lower portion of the T-connection 9, a tube 13 made of relatively frail material and having a solid end 14, over which fits a heavy depending rod 15 which is held in place by means of a cotter pin 16, which passes through the upper portion 17 of the heavy depending rod 15, 65 and through the solid end 14.

The upper gas chamber 12 may be equipped with any ordinary intake valve 18 such as used in loading or filling gas chambers, or the upper gas chamber 12, may be 70 filled through the valve 11. It will also be seen that the circular chamber 1 will also be filled when the valve 11 is open, or through valve 19.

If desired, the upper gas chamber 12 may 75 be eliminated and the gas used confined only to the circular chamber 1.

Persons attempting to open a safe in an unauthorized manner often use a hammer or sledge and break off the central knob 6 carrying the dial 5. When this central knob 6 has been removed, the burglar then "drifts" the safe by using a punch and driving the lock shaft 7 inwardly. If this manner of breaking into the safe is attempted on a safe 85 equipped with my device, the circular chamber 1, which is secured to the safe door insecurely, will easily yield to force. When this circular chamber 1 has been broken away from its holdings, the tube 8 is sheared or 90 broken and causes an exit for the gas or gases contained in one or both of the gas chambers. In the event, however, the central knob 6 is removed by drilling or other means without disturbing the circular chamber 1 and 95 the lock shaft 7 driven inwardly, this shaft will force the heavy depending rod 15 inwardly thereby fracturing or breaking the tube 13, resulting in making an exit for the gas or gases. A set screw 20 holds the heavy 100 depending rod 15 in desired relation with the lock shaft 7.

What I claim is:—

1. In a device of the class described, the combination of a circular chamber positioned 105 around a central knob carrying a dial, means for securing said circular chamber to the outer surface of a safe door, an upper gas chamber, and a frail tube communicating with said circular chamber and also communicating 110 with said upper gas chamber, substantially as described for the purpose set forth.

2. In a device of the class described, a circular gas chamber positioned on the outer surface of a safe door and surrounding a central knob and dial, a tube communicating with said circular chamber, a tube leading to an upper gas chamber, a valve between the tubes of said gas chambers, a frail depending tube with upper end communicating with

10 said gas chamber and having a solid end, a heavy depending rod attached to said frail tube, said heavy depending rod positioned directly back of the lock shaft, substantially as described for the purpose set forth.

In testimony whereof I affix my signature.

DOMENICK RUFF.
